Demeure & Mauritz.

Bed Bottom,

N° 10,010

Patented Sep. 13, 1853.

UNITED STATES PATENT OFFICE.

P. DEMEURE AND A. MAURITZ, OF NEW YORK, N. Y.

BED-BOTTOM.

Specification of Letters Patent No. 10,010, dated September 13, 1853.

To all whom it may concern:

Be it known that we, PIERRE DEMEURE and AUGUSTE MAURITZ, of the city, county, and State of New York, have invented a 5 certain new and useful Improvement in Bed-Bottoms; and we do hereby declare that the following is a full, clear, and exact description of the same, reference being made to the annexed drawing, making a part of 10 this specification, which is an isometrical view of our invention.

Our invention consists in an improved construction of spring bed bottoms and bedsteads in combination therewith. 15 The improvement in the spring bottom consists in giving elasticity transversely in combination with the vertical action of the spiral springs. In the old spring mattresses this quality is wanting and the consequence 20 is that a person lying upon one side of such a mattress will feel a tendency to roll off; the whole surface inclining toward that edge, for the straps which lace the springs together being rigid, cant over or incline 25 to one side such of the springs as are not being laid upon. In our improvement this is all avoided as the elasticity of the lateral or connecting wires so entirely prevents this that a person lying upon any part of the 30 bed will only compress the springs directly under him and will be supported equally on all sides.

At A A' is the frame of the bed-bottom which I prefer to have of metal.

35 B are a series of cross bars for supporting the spiral springs C of the ordinary construction.

Level with the frame A a series of long 40 spiral springs are secured so as to form a net work as seen at D. The vertical spiral spring C stand in the square spaces formed by the net and are secured to these by four straps or links from opposite sides as seen

at the letter (e). It is evident that the elasticity of the netting will enable those vertical springs to act to support a person, which are immediately under him and at his sides, allowing said springs to rise up on both sides alike, even though he may be near the edge, and secondly there will be 50 sufficient spring however near the edge to insure comfort in sleeping which is not the case upon the old mattresses having a rigid webbing at the top. To combine a folding bedstead with these springs: F and F' are 55 the head and foot boards; these are hinged to the ends of the frame A so as to be capable of folding down upon the springs and when set up to open no wider than proper. A framing to which the legs are attached is 60 hinged also to A as seen at G; the leg G' being nearly at right angles to G. A brace bar H extends from where G joins the legs to the lower rail of the bed bottom A'. This keeps the legs in their vertical position and 65 supports the bed.

By uncoupling the bolt H' the legs will fold under and lie parallel with the rail A'. Thus the bedstead can be transported with the mattress without increasing the space 70 occupied by the latter.

What we claim as our invention and desire to secure by Letters Patent is—

The manner of constructing the spring mattress by combining the vertical springs 75 with an elastic or spring net-work of spiral metallic springs for supporting said vertical springs, or for increasing the elasticity so that a person lying upon the bed will be equally supported on all sides as described. 80

PIERRE DEMEURE.
AUGUSTE MAURITZ.
